UNITED STATES PATENT OFFICE.

JEREMIAH GURLY FREDERICK, OF GARRISON, TEXAS.

CULTIVATOR.

1,086,761.

Specification of Letters Patent.

Patented Feb. 10, 1914.

Application filed April 4, 1913. Serial No. 758,992.

To all whom it may concern:

Be it known that I, JEREMIAH G. FREDERICK, a citizen of the United States, residing at Garrison, in the county of Nacogdoches and State of Texas, have invented a new and useful Cultivator, of which the following is a specification:

This invention relates to cultivators, its principal object being to provide means whereby the teeth of the cultivator, which are disposed in series arranged at opposite sides of the draft tongue, can be adjusted relative to each other and securely held in any position to which they may be moved.

15. A further object is to provide a device of this character which is simple and durable in construction and can be quickly and easily adjusted.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

20. In the accompanying drawings the preferred form of the invention has been shown.

In said drawings: Figure 1 is a plan view of the cultivator. Fig. 2 is a side elevation thereof. Fig. 3 is a section on line A—B Fig. 1. Fig. 4 is a transverse section through a tooth and through the means employed for attaching it to the cultivator. Fig. 5 is an enlarged detail view showing 25 one of the locking devices.

Referring to the figures by characters of reference 1 designates the draft beam, there being handles 2 at the rear end thereof. Secured to this beam at any suitable point in 30 advance of the handles is a large circular rack 3 which is secured in any suitable manner against rotation relative to the beam 1 and extends under the beam. Secured to the beam 1 and extending under the middle 35 portion of the rack 3 is a block 4, this block extending longitudinally under the beam. Pivotedly connected to the front end portion of the block are the lapping inner ends of front cross strips 5, each of these strips being 40 preferably formed of metal rolled to L-shape, the upwardly extending flanges of

the strips being cut away adjacent their inner ends, as shown at 6 in Fig. 5 so as not to interfere with the independent angular adjustment of the strips. Pivotedly connected to the back portion of the block 4 are additional angle strips 7 the inner ends of which lap and are pivotally mounted preferably upon the bolt 8 which extends through the center of the rack 3. Pivotedly 45 connected to the back cross strips 7 are clips 9 having inturned terminals 10, the middle portion of each clip having a bolt 11 extending therefrom and through the adjacent strip 7 so that the clip is thus free to 50 rotate upon the bolt. Each clip 9 tightly embraces the intermediate portion of a spring tooth 12, this spring tooth being extended rearwardly and downwardly as shown. The forward end of each spring tooth is pivotally connected to one of the front strips 5 by means of a bolt 13 or the like. Links 14 are mounted on the outer end bolts 13 and also on the outer end bolt 11, as shown in Fig. 1, these links 14 serving to hold the strips 5 and 7 properly spaced without subjecting the spring teeth to undesirable strains. The rear cross strips 7 have braces 15 secured thereon, the inner ends of the braceslapping and resting 55 on the beam 1 and being pivotally mounted on the bolt 8.

It will be apparent that each strip 7 is constantly parallel with the strip 5 in front thereof and said strips, together with beam 1 and links 14, constitute parallelograms. Furthermore the teeth 12 are constantly maintained parallel although, by adjusting the strips 5 and 7 angularly about their respective pivots, these teeth 12 can be caused 60 to move toward or from each other although maintaining their parallel relation. Mounted on each strip 7 so as to straddle the upstanding flange thereof, is a dog 17 which is U-shaped in cross sectional contour so as 65 to snugly straddle the flange. As the dog is U-shaped, it will be apparent that two rack engaging edges will be produced at its active end and, therefore, when the dog is in engagement with the rack, said edges will be 70 seated in adjoining notches while one tooth extends into the dog. A spring 18 is mounted on each strip 7 and is secured thereto, one end of the spring engaging the dog so as to hold said dog normally in active position.

When it is desired to adjust the cultivator, the dog 17 on one of the strips 7 is shift-

ed out of normal position so as to disengage its active end from the rack 3. Said strip 7 is then swung about its pivot bolt 8 until it assumes any desired angle relative to the beam 1 and, during this movement, strip 5 will be carried therewith. Furthermore the teeth 12 will also be shifted. As soon as the strips have been brought to the desired positions, dog 17 is released and will promptly shift into engagement with the rack 3 thus locking the strips against further movement relative to the beam. After one strip 7 and the teeth carried thereby has thus been adjusted, the other strip 7 can be similarly adjusted. Obviously the strips 7 at the two sides of the cultivator can be brought to any desired positions relative to each other. In Fig. 1 the two strips 7 have been shown in alinement and extending diagonally relative to the beam. Obviously, however, the two strips can be extended at right angles to the beam or both of them can be arranged so as to converge either forwardly or rearwardly.

By providing the clips 9, it becomes unnecessary to perforate the teeth 12 at points between the ends thereof. Thus the teeth are much stronger than would be the case should such perforations be used.

What is claimed is:—

- 90 1. A cultivator including a beam, a circular rack secured at its center thereto and extending thereunder, front cross stripslapping at their inner ends and mounted to swing independently relative to the beam, rear angle strips pivotally connected at their inner ends to the beam in alinement with the axis of the rack, each of said angle strips having its flange extended upwardly, teeth

pivotally connected to the cross strips and parallel with the beam, the cross strips at 40 each side of the beam being adjustable angularly independently of the other cross strips, and means straddling and pivotally connected to the flange of each rear cross strip for engaging the rack to hold the cross 45 strip against angular movement.

2. A cultivator including a draft beam, a circular rack extending thereunder, a bolt extending through the center of the rack and the beam, angle strips pivotally mounted on said bolt and extending in opposite directions from the beam, said strips being separately movable upon the bolt, locking elements straddling the flanges of the respective strips and normally engaging the 55 rack to hold the strips against movement about their pivots, front cross strips lapping at their inner ends and pivotally connected to the beam, teeth pivotally connected to the last named cross strips and extending 60 under the other or angular cross strips, links connecting the front and rear cross strips at their outer ends, clips pivotally connected to the rear cross strips and embracing the teeth, and braces extending over 65 the beam and mounted on the central bolt of the rack, said braces diverging downwardly and being attached to the respective angular cross strips.

In testimony that I claim the foregoing 70 as my own, I have hereto affixed my signature in the presence of two witnesses.

JEREMIAH GURLY FREDERICK.
